Filed Apr. 18, 1974, Ser. No. 461,965

Term of patent 14 years

Int. CL D23—01

U.S. CL. D23—40

FIG. 1 is a perspective view of a valve receiving tubing fitting embodying my novel design;

FIG. 2 is an end elevational view thereof;

FIG. 3 is a side elevational view thereof;

FIG. 4 is a bottom plan view thereof;

FIG. 5 is an end elevational view of a modified form of the valve receiving tubing fitting shown in FIG. 1;

FIG. 6 is a side elevational view of FIG. 5;

FIG. 7 is a bottom plan view of FIG. 5; and

FIG. 8 is a top plan of either form.

The broken line representation of a tube in FIGS. 1, 2 and 5 and the broken line representation of a valve in FIGS. 2 and 5 are for purposes of illustration only.

I claim:

The ornamental design for valve receiving tubing fitting, substantially as shown and described.
